UNITED STATES PATENT OFFICE.

WILLIAM E. WILDER, OF BROOKLINE, MASSACHUSETTS.

RAILWAY SNOW-PLOW.

SPECIFICATION forming part of Letters Patent No. 674,330, dated May 14, 1901.

Application filed February 19, 1901. Serial No. 47,918. (No model.)

To all whom it may concern:

Be it known that I, WILLIAM E. WILDER, of Brookline, in the county of Norfolk and State of Massachusetts, have invented certain 5 new and useful Improvements in Railway Snow-Plows, of which the following is a specification.

This invention relates to railway snow-plows, and among its objects are the following: First, to provide a plow having a snow-clearing end or prow so located as to follow the track in rounding curves; second, to provide means for deflecting the snow thrown up by the prow, so as to return it to the roadway 15 close to the track, and, third, to provide an adjustable share of improved construction.

Of the accompanying drawings, forming a part of this specification, Figure 1 represents a side elevation of a double-ended snow-plow 20 constructed in accordance with my invention. Fig. 2 represents a plan view thereof. Fig. 3 represents, on an enlarged scale, a side elevation of the front end of the plow, partly broken away. Fig. 4 represents a transverse 25 vertical section taken between the trucks. Fig. 5 represents a plan view of one of the prows and truck. Fig. 6 represents a detail vertical section taken through one of the hinge-joints connecting the adjustable share 30 to the front end of the plow. Fig. 7 represents a similar section taken at one side of the middle hinge-joint. Fig. 8 represents a plan view, partly broken away, showing one 35 of the hinge-joints. Figs. 9, 10, and 11 represent sections on the correspondingly-numbered lines of Fig. 7.

The same reference characters indicate the same parts in all of the figures.

In the drawings, 1 represents a plow-body 40 whose ends are pivotally supported on two trucks 2 2, which are adapted to turn with respect to the body in rounding curves. The king pins or pivots 3 3, connecting the body with the trucks, are in each instance located 45 substantially over the middle of the wheel-base of the truck, and the body terminates substantially at its point of support. Each truck is provided with a shovel-nosed prow or snow-clearing end 4, which may have any 50 approved construction either to throw the snow to both sides of the track or to one side only, said prows being secured by bolts 5 5,

Fig. 4, to the truck-frames 6, so as to swing with the trucks in rounding curves, as indicated by the dotted lines in Fig. 2. This is 55 an important advantage, particularly on street-railways, which frequently have abrupt curves. In such a case a plow having a prow attached to the body would project a considerable distance outside of the track in rounding 60 curves and would not properly clear the track. A prow mounted upon the truck will always follow the track and will properly clear the same in rounding curves. This construction also allows the plow to be made 65 of substantial length, giving ample accommodations for a crew, together with proper stability and weight. For street-railway work a plow of this character may with advantage be provided with its own motor. In 70 the drawings the body 1 is shown as equipped with a trolley 7, adapting it for use on an overhead electric system, and one or both (preferably both) of the trucks 2 2 are provided with motors 8, operating upon the axles 75 in the usual manner. By thus placing the point of application of the propelling power at the point of resistance—namely, on the truck—the body 1 is relieved of strains due to snow encountered by the prow 4. The 80 weight of the motor, furthermore, gives increased stability to the truck and tends to keep it on the rails.

As shown in Fig. 3, the journal boxes or bearings 9 9 of the front and rear wheels 10 11 85 are mounted in guides or pedestals 12 12 on the truck-frame 6. Springs 13 are interposed between the journal-boxes 9 of the rear pair of wheels 11 and the truck-frame in order to allow the rear journals to yield vertically and 90 absorb concussions; but above the forward journals 9 I provide, in place of the springs, blocks 14 of rigid material, such as wood, which prevent a downward yielding of the forward end of the truck-frame toward the 95 forward axle. The object of this construction is to prevent the forward edge of the prow 4 from approaching nearer than a predetermined distance to the rails, whereby it avoids encountering low obstructions on the 100 track. Since the body 1 rests on the middle of the truck-frame, the front axle acts as a fulcrum and gives the body the benefit of the springs 13. The prows 4 are bolted to the

upper faces of the pedestals 12, over the wheel-axle journals, whereby the weight of the prow is directly borne by the journals rather than by the middle of the truck-frame.

5 At the lower front end of the prow 4 is located a share 15, which is provided with a cutting edge and is hinged so as to raise or lower this edge. The hinging of the share enables it to be lifted away from the rails, as indicated in dotted lines in Fig. 3, thus avoiding an accumulation of snow or ice below the share in running backward, which would have a tendency to lift the plow from the rails. This tendency is encountered principally where 15 the under side of the prow is inclined toward the share or cutting edge, enabling the snow or ice to wedge underneath the share in running backward. Such pivoted shares are of particular utility on a double-ended plow, 20 for on this kind of a plow one of the prow's of necessity always runs backward, and by raising the share at that end derailment is prevented. An operating-lever 16, connected by a link 17 with the share 15, is provided 25 for moving the share in the described manner. This operating mechanism being located wholly behind the front of the prow 4 and below its sloping upper surface is protected within the prow and presents no obstruction to the passage of the snow over the 30 prow. A smooth upper surface for the prow is further obtained by locating the hinge which connects the rear portion of the prow with the share 15 wholly below the said upper surface. The construction of the lower 35 front end of the prow is shown in detail in Figs. 5 to 11, inclusive. 18 18 are a series of sloping longitudinal beams or sills forming part of the frame of the prow and having 40 abrupt end faces 19 at their lower ends. A strong and durable construction is given to the share 15 by providing it with a framework composed of a series of triangular brackets 20 20, to which plates 21 22, forming the upper and lower surfaces of the share, are secured by rivet-pins 23 23. These brackets also constitute hinge members, which are embraced by other hinge members or plates 24 24, bolted to the beams 18, said plates being 45 connected to the brackets 20 by hinge-pintles 25 25. As indicated in Fig. 9, the upper plate or cutter 21 is bent or flanged over on each edge, as at 27, to form the sides of the share. These flanges impart additional strength to 50 the share to withstand blows and add stiffness to the plate in a forward and rearward direction, which prevents its tendency to buckle in that direction. In the lowermost or operative position of the share 15 the rear sides of the 55 brackets 20 abut against the end faces 19 of the beams 18 and find there an ample and strong bearing to resist the downward strain on the share, such strains being transmitted to the beams 18 in the direction of their length, 60 whereby the greatest stiffness is secured with the least weight and material.

The prow's 4 shown in the drawings are provided with upwardly and outwardly inclined moldboards 28 28, from the upper ends of which the snow lifted by the nose of the 70 prow is discharged at the side of the roadway. In cities or towns this discharge is sometimes objectionable to passing traffic or persons, and to obviate it I provide the overhanging deflectors 29 29, located at the upper 75 ends of the moldboards 28 and inclined outwardly and downwardly, so as to divert the snow in a corresponding direction. These deflectors are hinged at 30 along their inner edges to the prow's 4 and are attached to 80 cords 31, which pass inside of the body 1, whereby the operator is enabled to throw the deflectors into an inoperative vertical position, as represented in full lines at the left of Fig. 4. They may be fixed in this inoperative 85 position by suitable means, such as a pin 32. Springs 33 surrounding the hinge-pintles of the deflectors 29 tend to hold them in their operative positions.

I claim—

1. A railway snow-plow comprising a body, a wheeled truck pivoted to and supporting said body, a snow-clearing end or prow mounted on the truck, and substantially covering the whole of its front end, and adapted to 95 turn therewith independently of the body.

2. A railway snow-plow comprising a wheeled truck, a body supported by said truck, said body terminating substantially over the middle of the wheel-base of the truck and being pivoted thereto to the truck, and a snow-clearing end or prow mounted on the truck and substantially covering the whole of its front end.

3. A railway snow-plow comprising a body, 105 a wheeled truck pivoted to and supporting said body, a motor mounted on said truck for propelling the plow, and a snow-clearing end or prow mounted on the truck, and adapted to turn therewith independently of the body.

4. A double-ended railway snow-plow carrying its own motor and comprising a body, wheeled trucks pivoted to and supporting opposite ends of said body, and oppositely-directed snow-clearing ends or prow's mounted 115 on the respective trucks, and adapted to turn therewith independently of the body.

5. A double-ended railway snow-plow carrying its own motor and comprising a body, wheeled trucks pivoted to and supporting opposite ends of said body, and oppositely-directed snow-clearing ends or prow's mounted on the respective trucks and substantially covering the whole of their outward ends, and adapted to turn therewith independently 125 of the body.

6. A railway snow-plow comprising a truck having a frame, front and rear wheels, bearings for the rear wheels, springs interposed between said bearings and the frame, bearings for the front wheels rigid with the frame, 130 a snow-clearing end or prow mounted on the

truck, and a body supported by the truck and pivoted to the frame between the forward and rear wheels.

7. A railway snow-plow having an upwardly and outwardly slanted snow-clearing end or prow, and an overhanging downwardly and outwardly slanted side deflector adapted to downwardly deflect the snow thrown up by said prow, said deflector being adjustable to 10 assume operative and inoperative positions.

8. A railway snow-plow having an upwardly and outwardly slanted snow-clearing end or prow and an overhanging downwardly and outwardly slanted deflector hinged along its 15 inner edge to the side of the plow so as to assume operative and inoperative positions, and adapted to downwardly deflect the snow thrown up by said prow.

9. A railway snow-plow having a snow-clearing end or prow provided with an inclined upper surface, and a share hinged along the lower front edge thereof, the hinge being located below the upper surface of the 20 prow so as to leave said upper surface smooth and unbroken at the joint.

10. A railway snow-plow having a snow-clearing end or prow provided with an inclined upper surface, a share hinged along the lower front edge thereof, and mechanism 25 for oscillating said share, said mechanism being located within and below the said upper surface.

11. A railway snow-plow having a snow-clearing end or prow provided with longitudinal frame-beams having abutments at their 30

forward ends, and a share hinged to the forward edge of the prow, and having frame-brackets at intervals alined with the said beams and provided with offset portions adapted to rest against said abutments at the 40 lowermost adjustment of the share, whereby the said beams directly receive the thrust of the brackets in the direction of their length.

12. A railway snow-plow having a share or nose constructed with triangular metallic 45 brackets forming a frame and a top plate or cutter riveted to said brackets.

13. A railway snow-plow having a share or nose constructed with triangular metallic brackets forming a frame and top and bottom 50 plates riveted to said brackets.

14. A double-ended railway snow-plow having oppositely-directed snow-clearing ends or prows at its respective ends, the outward-operating portions of which are inclined on their 55 under sides, and horizontal shares at said outward ends hinged to the prows so as to be capable of being raised and lowered.

15. A railway snow-plow having a body, a truck pivoted thereto, and comprising a frame, 60 wheels, axles, and axle-journals, and a snow-clearing end or prow attached to and supported on said frame at points substantially over the journals of the axles.

In testimony whereof I have affixed my 65 signature in presence of two witnesses.

WILLIAM E. WILDER.
